G. W. WREN.
MANUFACTURE OF GAS FROM PETROLEUM.

No. 86,793.

Patented Feb. 9, 1869.

United States Patent Office.

GEORGE W. WREN, OF BROOKLYN, NEW YORK, ASSIGNOR TO URA-NIA E. WREN, OF SAME PLACE

Letters Patent No. 86,793, dated February 9, 1869

IMPROVEMENT IN THE MANUFACTURE OF GAS FROM PETROLEUM.

The Schedule referred to in these Letters Patent and making part of the same.

To all whom it may concern:

Be it known that I, GEORGE W. WREN, in the city of Brooklyn, county of Kings, State of New York, have invented a new and improved Apparatus for the Manufacture of Illuminating-Gas from the Basis of Crude Petroleum; and I do hereby declare that the following is a true and exact description of the same, reference being had to the accompanying drawings, and to the letters of reference marked thereon.

The nature of my invention consists in producing illuminating-gas from a basis of crude petroleum, or cognate materials, by the following process; that is to say—

I place in a furnace, properly constructed for the purpose, which is shown in the drawings, at Figure 1, a retort.

To enable others skilled in the art to make and use my invention, I will proceed to describe its construction and operation.

I construct my furnace in any of the known forms by which I can produce an intense heat on the retort placed in it, said retort being constructed or divided into four longitudinal sections, the partitions being so placed, and shortened and lengthened at either end, that, after the covers, Figures 4 and 5, are placed on the end of the retort, the chambers or sections shall be so connected that they lead from one into the other, with grooves on the lids, as shown at M, to fit over the partitions, that come flush with the end of retort, and a lip, to project a short distance inside its circumference, to make a tight joint, the four sections producing, in effect, one retort of four times the length of the one described, and producing more gas, from a given amount of petroleum, than four separate retorts, connected together by pipes, in one furnace.

The sectional view of the retort is shown at Figure 2. The end views, at Figure 3 and Figure 6.

It is immaterial which end is the front or back, but we will call fig. 3 the front, and fig. 6 the back.

On the front end, fig. 3, the partitions N O Q come flush with the end of the retort, while the partition P is from four to eight inches shorter, as the case may be, which makes a connection between the two lower sections, marked E and F, when the cover, fig. 5, is placed and secured by a bar, marked K, fig. 1, the cover having grooves in it, marked M, said grooves being sufficiently wide, and the lips of the grooves sufficiently prominent, to hold a packing of clay and putty mixed, or other suitable material, to make a tight joint, to prevent the gas from escaping, or leaking from one partition to the other.

Then, at the rear end, fig. 6, the partitions N P come through flush with the end, and the partitions O Q are from four to eight inches shorter, leaving a connecting space from D to E and F to G.

When the cover, fig. 5, is placed to close the end, secured in its place by a bar marked K, fig. 1, the straight grooves M, in the cover L, fig. 5, correspond to and fit over the partitions marked N P, fig. 6, and the triangular grooves, marked M, fig. 4, correspond to and fit over the partitions N Q O, fig. 3.

Now we will suppose the retort placed in a proper furnace, with the covers luted and in position on both ends of the retort, held in their places by the bars, marked K, as shown at fig. 1, with the inlet-siphon pipe, marked C, in its place, entering chamber D, as shown at fig. 3, and fig. 2, and fig. 1, with the outlet-pipe, marked H, as shown in fig. 3, and fig. 2, and fig. 1, which outlet-pipe leads to the gas-holder, (not shown.)

I will proceed to show how I make gas. I first heat my retort to an intense red heat. I then introduce a stream of petroleum through the siphon C into the chamber D, at the front end of the retort, fig. 3. The petroleum passes the whole length of the retort, to the other end, fig. 6, when it passes around the end of the partition O, down to the chamber E; through the chamber E, the length of the retort, to the front end again. Thence, around the partition P, at the front, to the chamber F; through the chamber F the length of the retort, to the rear end again, fig. 6. Thence, upward, around the partition Q, into the chamber G. Thence, through the chamber G, the length of the retort, to the front, then out, through the outlet-pipe H. The petroleum, in its circulation through the retort, backward and forward, becomes changed, and finally passes out of the outlet-pipe H in the form of gas, to the holder, without leaving any residuum except a little free carbon, which may be removed periodically by taking off one or both the lids. I make the retort with two lids, as described, for greater facility of casting it and the partitions perfectly, and for facility of cleaning.

Claims.

1. I claim the construction of retort with partitions, so as to make a fourfold retort, as described.
2. I claim the construction of the chambers, to allow a free circulation from one end to the other, backward and forward, and forward and backward, for this purpose, as described.
3. I claim the grooves on the lid of the retort, for the purpose of connecting the separate chambers.
4. I claim the grooves on the lid, as described, in combination with the lips on its circumference.
5. I claim so constructing one retort as to be, in effect, more than three retorts, for the purpose specified.

GEORGE W. WREN. [L. s.]
